UNITED STATES PATENT OFFICE.

WILLIAM S. HAMM, OF HUBBARD WOODS, ILLINOIS, ASSIGNOR TO THE ADAMS & WESTLAKE COMPANY, A CORPORATION OF ILLINOIS.

SASH-LATCH.

1,353,834.

Specification of Letters Patent. Patented Sept. 28, 1920.

Application filed September 16, 1919. Serial No. 324,162.

To all whom it may concern:

Be it known that I, WILLIAM S. HAMM, a citizen of the United States, and resident of Hubbard Woods, county of Cook, and State 5 of Illinois, have invented certain new and useful Improvements in Sash-Latches, of which the following is a specification, and which are illustrated in the accompanying drawings, forming a part thereof.

10 The invention relates to latches for window sash, and is intended primarily for use in connection with windows of railway cars.

The present practice involves the use of latches which are easily released, and in case 15 of being out of repair, as by the breaking of the bolt or a spring or the loosening of holding screws, will fail to support the sash. Serious accidents result, as travelers not infrequently rest their hand or arm on the 20 window sill and receive the full force of the falling sash. Careless or unintelligent manipulation of sash latches, especially by children also frequently occasion similar accidents.

25 The objects of the present invention are to guard against a too ready release of a sash latch, to so arrange the parts that a portion of the bolt interlocking with the casing will also be interlocked with the sash, and to 30 prevent detachment of the latch casing or the accidental retraction of the bolt should the latch mechanism be loosened from its attachment to the sash, or be out of order.

While the objects in view may be secured 35 by various forms of construction, certain embodiments of the invention are herein-after described and are illustrated in the accompanying drawings in which,

Figure 1 is a detail elevation of a window 40 equipped with the improved latch;

Fig. 2 is a detail, partly in section, viewed from the line 2—2 of Fig. 1;

Fig. 3 is a sectional detail on the line 3—3 of Fig. 2;

45 Fig. 4 is an inside view of the latch detached;

Fig. 5 is a detail of a preferred form of stop device;

Fig. 6 is a detail of the sash with the 50 latch removed;

Fig. 7 is a detail elevation of the window showing a modified form of construction of the latch;

Fig. 8 is a detail of the stop device as 55 shown in Fig. 7;

Fig. 9 is a view similar to Fig. 1 showing a further modification;

Fig. 10 is a sectional view on the line 10—10 of Fig. 9;

Fig. 11 is a detail in perspective of the 60 keeper shown in Figs. 9 and 10; and

Fig. 12 is a detail view of a sash, sash stop and detent for supporting the sash, as from line 10—10 of Fig. 9 illustrating the broader concept of the invention. 65

There is shown in the drawings a window casing comprising a side portion 10 and sill 11, with the usual stops 12, 13, forming a runway for the sash 14.

The latch comprises a casing 15, of any 70 suitable form, shown as being applied to the surface of one of the sash rails and secured by means of screws, as 16, and as being provided with a fixed grip member 17. Within the casing is mounted a reciprocating bolt 75 18, normally advanced by means of a spring 19 coiled about its shank and reacting between the end wall of the casing and a lug 20 fixed to the bolt. A lever 21, here shown as in the form of a bell-crank, is pivoted 80 within the casing at 22, one of its arms engaging the front face of the lug 20, and its other arm projecting through a suitable aperture in the rear wall of the casing and constituting a thumb-piece 23 located above 85 the member 17. By downward pressure on the thumb-piece 23 the bolt is retracted against the resistance of the spring 19. In operating the bolt the user may conveniently grasp the members 17 and 23 between his 90 finger and thumb.

The bolt co-operates with one or more keepers attached to the window casing. Preferably a plurality of keepers are provided and for convenience of attachment are 95 formed on a single bar 24, which in in the art is known as a rack bar, and is secured to the casing stop 12 by means of screws.

The several keepers take the form of a series of shoulders, as 25, which co-operate 100 with the latch bolt to hold the sash at any desired elevation. Each shoulder is preferably downwardly inclined toward the plane of the sash, in order that as the bolt rests upon it the sash will be cammed outwardly 105 against the stop 13 for the purpose of preventing rattling. The inner portion of each shoulder is recessed, thereby forming at its outer portion a flange or shoulder 26 which co-operates with a shoulder on the bolt here 110

2
formed by providing a lateral recess or notch 27 in the bolt. The sash being raised to such position that the bolt is above one of the keepers and is extended, is allowed 5 to descend sufficiently to engage the bolt with the keeper, the notch 27 interlocking with the flange 26, thus preventing the withdrawal of the bolt either accidentally or by the manipulation of the lever or under 10 the influence of vibration should spring be weakened or broken, or should the latch casing become loosened, until the sash is again slightly raised. Preferably the inwardly 15 facing portion 28 of the bar 24, above each of the keepers, is inclined inwardly and upwardly for camming the bolt inward as the sash is raised, thus rendering it unnecessary to manipulate the lever 21 in raising the sash.

20 The bolt 18 is so disposed within the casing 15 that it lies at least partially within the sash rail. Preferably the latch casing is provided with an integral apertured block 29, as shown, forming a bearing for 25 the outer end of the bolt and reinforcing it against lateral stress. This block is entered into the sash and prevents the separation of the latch casing therefrom should the holding screws be loosened or removed, so 30 long as the casing is adjacent to one of the keepers.

Should the spring 19 be broken or weakened, or should the holding screws of the casing be loosened, or should the latch become defective for any other reason, the sash will, nevertheless, be securely held by the bolt for the reason that the latter cannot be retracted because of the interlocking of its notch with the flange 26 and the partial embedding of the bolt within the sash. Even if the holding screws were entirely removed, the bolt would be held in place until the sash were slightly raised to disengage it from the rib 26 and the casing could not be removed from the sash until it is raised above the rack or an individual keeper, when the rack bar form is not employed.

It is observed in practice that travelers, especially children, not infrequently rest one hand upon the sill and attempt to manipulate the latch with the other, and serious accidents have occurred by reason of the violent dropping of the sash. By the 55 construction shown and described the interlocking of the bolt shoulder with the flange 26 effectually prevents such accidents as it renders it difficult to release the latch without employing both hands.

60 While a preferred form of construction is shown in Figs. 1 to 6, the invention may, nevertheless, be embodied differently. For example, in Figs. 7 and 8 there is shown a construction in which the keeper 30 is provided with a transverse flange or lip 31 for

engaging a recess 32 crossing the lower face of the bolt, and which will effectually prevent the bolt from being jarred back should the spring be broken, or from being manually retracted without raising the sash.

In Figs. 9, 10 and 11 a further modification is shown. The window casing, the sash, and the latch mechanism are the same as in Figs. 1 and 5. The keepers take the form of approximately half round loops 33 formed in a metal strip 34 which is secured to the sash engaging face of the stop 12, the loops 33 being entered into the stop.

When advanced the bolt 18 enters into one of these loops 33. In order to prevent the accidental withdrawal of the bolt the loops 33 are somewhat elongated vertically, and each is provided at its outer margin and adjacent its lower end with a shoulder 35, for engaging the bolt shoulder heretofore described. The shoulder 35 is provided in this instance by forming a rib in the loop and the bolt shoulder by a transverse recess across the lower face of the bolt. In this construction as in that of Figs. 1 to 5 the advantage of having the bolt partially embedded within the sash and partially within the keeper is obtained, as is also the advantage of having the bolt interlocked with the keeper to prevent its withdrawal until the sash shall have been slightly raised.

Fig. 12 is a diagrammatic view for the purpose of more clearly illustrating the feature of interlocking the sash with the casing stop by means of a detent in the form of 100 a bolt or plug which enters an aperture, formed in part within the sash and in part within the stop. In practice this detent takes the form of a latch bolt but obviously the sash might be thus secured by the use of 105 a simple peg which would fit within the aperture.

I claim as my invention:

1. In combination, a window casing having a sash stop, a sash fitting within the 110 casing and slidably engaging the stop, and a detent adapted to enter between the sash and stop and to extend laterally into each.

2. In combination, a window casing having a sash stop, a sash fitting within the 115 casing and slidably engaging the stop, and a detent adapted to enter between the sash and stop and to extend laterally into each, such detent having a lateral shoulder and the recess in the keeper being vertically 120 wider than the portion of the bolt received by it and having a shoulder at its lower portion engageable back of the detent shoulder.

3. In combination, a sash latch comprising a reciprocable bolt adapted to be partially laterally embedded in a sash, and a keeper carried by the casing for the sash and adapted to partially laterally receive the bolt.

4. In combination, a window casing hav-

ing a sash stop, a sash fitting within the casing and slidably engaging the stop, a latch secured to the sash and having a reciprocable bolt partially laterally embedded 5 in the sash, and a keeper secured to the stop and adapted to partially laterally receive the bolt.

5. In combination, a sash latch comprising a reciprocable bolt adapted to be partially laterally embedded in a sash, and a keeper carried by the casing for the sash 10 and adapted to partially laterally receive the bolt, such bolt having a lateral shoulder adapted to engage a shoulder on the keeper.

15. 6. In combination with a sliding sash and its casing, a latch comprising a casing attached to the sash and having a boss at its forward end fitting within a complementary recess in the sash rail, and a reciprocable 20 bolt slideable through the boss, and a keeper attached to the casing and having a bolt receiving recess open toward the face of the sash.

7. In combination with a sliding sash and

its casing, a latch comprising a casing attached to the sash and having a boss at its forward end fitting within a complementary recess in the sash rail, and a reciprocable bolt slideable through the boss, and a keeper 25 attached to the casing and having a bolt receiving recess open toward the face of the sash, the bolt and keeper being adapted to interlock when the sash is partially lowered with the bolt extended.

8. In combination with a sliding sash and 30 its casing, a latch comprising a casing attached to the sash and having a boss at its forward end fitting within a complementary recess in the sash rail, and a reciprocable bolt slideable through the boss, and a keeper 35 attached to the casing and having a bolt receiving recess open toward the face of the sash, the bolt having a lateral shoulder and the keeper having a shoulder engageable 40 back of the bolt shoulder when the sash is 45 partially lowered with the bolt extended.

WILLIAM S. HAMM.
